UNITED STATES PATENT OFFICE

104,991

DESIGN FOR AN INTERCHANGEABLE RUBBER HEEL

Howard Cairns, San Francisco, Calif.

Application November 9, 1936, Serial No. 65,808

Term of patent 3½ years

To all whom it may concern:

Be it known that I, Howard Cairns, a citizen of the United States of America, residing at San Francisco, in the county of San Francisco and State of California, have invented a new, original, and ornamental Design for an Interchangeable Rubber Heel, of which the following is a specification, reference being had to the accompanying drawing, forming a part thereof.

The figure is a perspective view of an interchangeable rubber heel, showing my new design.

I claim:—

The ornamental design for an interchangeable rubber heel substantially as shown.

HOWARD CAIRNS.
